FIG. 4.

UNITED STATES PATENT OFFICE

2,144,415

KNITTED FABRIC OR ARTICLE AND THE
PRODUCTION THEREOFRobert Kirkland Mills, Sherwood, Nottingham,
EnglandApplication May 19, 1937, Serial No. 143,603
In Great Britain May 25, 1936

7 Claims. (Cl. 66—169)

This invention is for improvements in knitted fabrics or articles and in the production thereof, and is concerned with ladder-resistant selvedged fabrics, or articles, produced on a flat or straight bar knitting machine, such as a machine of the Cotton's patent type. Considerable difficulty is experienced in making a good selvedge in fabrics which are ladder-resistant, and it is an object of the present invention to overcome this difficulty. With this object in view the invention, as viewed from one aspect, provides flat or selvedged knitted fabric embodying locked or tied stitches and characterized by a selvedge wherat thread extending from the termination of one course of loops (stitch loops or stitch locking loops) to the commencement of a subsequent course of loops is knitted to form one or more stitches which intermesh with previously and subsequently formed stitches at the selvedge of the fabric.

The invention is specifically concerned with fabric of the type comprising courses of stitch loops alternating with courses of locking loops, in which said locking loops extend through and around the stitch loops and the thread forming a course of locking loops is returned at the next course to form stitch loops and vice versa. In producing selvedged fabric of this type considerable difficulty has heretofore been experienced in forming an effective selvedge at that edge of the fabric wherat the carrier, having laid the thread for a course of locking loops, is reversed to lay the thread for the succeeding course of stitch loops. This difficulty is overcome by the present invention, which as viewed from another aspect, provides a knitted selvedged fabric of the type referred to, where in each course of locking loops terminates short of the selvedge edge and the thread extending from the last locking loop is formed into selvedge stitch loops meshing with previously and subsequently formed stitch loops.

In the preferred arrangement the said thread extending from the last locking loop forms a double loop in the succeeding course of stitch loops, and the said double loop is inwards of the selvedge loop. That is to say it occupies a wale other than the wale at the extreme edge of the fabric.

The invention also includes the production on a straight bar knitting machine of knitted fabric embodying stitches that are locked or tied by stitch-locking loops, characterized in that a thread carrier subsequent to being traversed the normal extent required for a stitch course has imparted thereto a comparatively short additional traverse to lay thread over a small number of additional needles, and said needles are operated to produce

knitted selvedge stitches intermeshing with similar selvedge stitches previously produced.

More specifically the invention provides a method of knitting selvedged fabric of the type referred to, in which the thread for a course of locking loops is supplied to a less number of needles than that to which it is supplied for a course of stitch loops and in which at the last formed end of a course of locking loops the thread from the last locking loop is fed to additional needles and the latter are operated to produce unlocked stitch loops intermeshing with similar stitch loops of a preceding course.

In order that the invention may be better understood reference will now be made to the accompanying drawings, in which Figures 1 to 4 inclusive show the successive steps in the method of producing a selvedge at that edge of fabric of the type referred to wherat the traverse of the thread carrier, after producing a course of stitch locking loops, is reversed to make a course of ordinary or plain stitch loops from the same thread.

The fabric embodies courses of stitch loops *a*, which loops *a* are locked at each course by locking loops *b*. That is to say courses of stitch loops *a* alternate with courses of locking loops. These alternating courses are laid, as will readily be understood, by the movement to and fro along the line of the needles by a thread carrier indicated at *D*, the said carrier being traversed in one direction to lay the thread for a course of stitch loops and then in the reverse direction to lay the thread for a course of locking loops whereby said stitch loops are locked.

At that phase in the stitch production shown in Fig. 1 the needles have been lowered to knock over a course of stitch locking loops *b*, the sinkers retracted, and the thread carrier *D*, during this initial projection of the sinkers, has been shogged out to the extent of two needles *N*¹, *N*², beyond the normal selvedge needle *N*³, this short movement of the carrier being from the position shown in broken lines to that shown in full lines. At this position the thread extends from the last formed locking loop *b* to the carrier within the top or bend of the beard of the normal selvedge needle *N*³, below the neb of the adjacent jack sinker *10* and over the divider sinker *11* and the last jack sinker *10a*. The needles now rise (Fig. 2) and the jacks and dividers are further projected therebetween, and the relative movement between the needles and sinkers may be such that the thread extending up from the fabric to the carrier passes to the front of the first additional selvedge needle *N*², and to the rear of the end

needle N¹, said thread passing back into the elongated throat 11a of the divider sinker 11. From this position the needles are fully projected to clear the locked stitch loops on to the needle shanks below the beards and to receive the next feed of thread (Fig. 3), and the carrier D is then traversed in a reverse direction across the needle row above the noses of the sinkers preparatory to producing the next course of stitches. In this way the thread extends up from the fabric in front of the shanks of needles N³ and N² and becomes wrapped round the shank of the end needle N¹. The subsequent retraction of the needles and pressing of same to produce a course of plain or unlocked stitch loops a forms a normal knitted stitch loop on the needle N³ and casts off said needle, along with a previously formed stitch loop, a bar b¹ of the thread fed during the aforesaid short shogging movement of the carrier at the end of the preceding course. On the needle N² a double-thread stitch is formed, while on the end selvedge needle N¹ a single thread stitch is formed, as shown in Fig. 4.

In this manner it will be appreciated that a strong and firm selvedge is produced which while having a compact and even structure possesses an elasticity or resilience equal or substantially equal to that of the remainder of the fabric.

I claim:—

1. A selvedged knitting fabric of the type comprising courses of stitch loops and courses of stitch-locking loops, wherein each course of stitch-locking loops terminates short of the selvedge edge and the thread extending from the last locking loop is formed into selvedge stitch loops meshing with previously and subsequently formed stitch loops.

2. Fabric according to claim 1, wherein said thread extending from the last locking loop forms a double loop in the succeeding course of stitch loops.

3. Fabric according to claim 1 wherein thread extending from the last locking loop forms the double loop in the succeeding course of stitch loops and wherein said double loop is located inwards of the selvedge loop.

4. A selvedge knitted fabric comprising courses of stitch loops alternating with courses of stitch-locking loops, wherein each course of stitch-locking loops terminates short of the selvedge edge and wherein beyond the last locking loop there is a few unlocked stitch loops constituted by the thread extending, from the said last locking loop, outwards to the selvedge loop and then back upon itself in the next course of stitch loops.

5. The production on a straight bar knitting machine of knitted fabric according to claim 1 embodying stitches that are locked or tied by stitch-locking loops, wherein a thread carrier subsequent to being traversed the normal extent required for a course of stitch-locking loops has imparted thereto a comparatively short additional traverse to lay thread over a small number of additional needles, and said needles are operated to produce knitted selvedge stitches intermeshing with similar selvedge stitches previously produced.

6. The production of fabric according to claim 1, wherein thread is traversed in one direction to produce normal stitch loops and in an opposite direction to produce loops that are passed through and also around said stitch loops to lock same, and wherein at the termination of each course of locked stitches the thread is carried to and fro over a comparatively small number of additional needles which are operated to produce intermeshing stitches other than locked stitches constituting a selvedge for the locked stitch fabric.

7. A method of knitting selvedged fabric according to claim 1, of the type comprising courses of stitch loops alternating with courses of stitch-locking loops, in which the thread for a course of locking loops is supplied to a less number of needles than that to which it is supplied for a course of stitch loops and in which at the last formed end of a course of locking loops the thread from the last locking loop is fed to additional needles and the latter are operated to produce unlocked stitch loops intermeshing with similar stitch loops of a preceding course.

needle N¹, said thread passing back into the elongated throat 11a of the divider sinker 11. From this position the needles are fully projected to clear the locked stitch loops on to the needle shanks below the beards and to receive the next feed of thread (Fig. 3), and the carrier D is then traversed in a reverse direction across the needle row above the noses of the sinkers preparatory to producing the next course of stitches. In this way the thread extends up from the fabric in front of the shanks of needles N³ and N² and becomes wrapped round the shank of the end needle N¹. The subsequent retraction of the needles and pressing of same to produce a course of plain or unlocked stitch loops a forms a normal knitted stitch loop on the needle N³ and casts off said needle, along with a previously formed stitch loop, a bar b¹ of the thread fed during the aforesaid short shogging movement of the carrier at the end of the preceding course. On the needle N² a double-thread stitch is formed, while on the end selvedge needle N¹ a single thread stitch is formed, as shown in Fig. 4.

In this manner it will be appreciated that a strong and firm selvedge is produced which while having a compact and even structure possesses an elasticity or resilience equal or substantially equal to that of the remainder of the fabric.

I claim:—

1. A selvedged knitting fabric of the type comprising courses of stitch loops and courses of stitch-locking loops, wherein each course of stitch-locking loops terminates short of the selvedge edge and the thread extending from the last locking loop is formed into selvedge stitch loops meshing with previously and subsequently formed stitch loops.

2. Fabric according to claim 1, wherein said thread extending from the last locking loop forms a double loop in the succeeding course of stitch loops.

3. Fabric according to claim 1 wherein thread extending from the last locking loop forms the double loop in the succeeding course of stitch loops and wherein said double loop is located inwards of the selvedge loop.

4. A selvedge knitted fabric comprising courses of stitch loops alternating with courses of stitch-locking loops, wherein each course of stitch-locking loops terminates short of the selvedge edge and wherein beyond the last locking loop there is a few unlocked stitch loops constituted by the thread extending, from the said last locking loop, outwards to the selvedge loop and then back upon itself in the next course of stitch loops.

5. The production on a straight bar knitting machine of knitted fabric according to claim 1 embodying stitches that are locked or tied by stitch-locking loops, wherein a thread carrier subsequent to being traversed the normal extent required for a course of stitch-locking loops has imparted thereto a comparatively short additional traverse to lay thread over a small number of additional needles, and said needles are operated to produce knitted selvedge stitches intermeshing with similar selvedge stitches previously produced.

6. The production of fabric according to claim 1, wherein thread is traversed in one direction to produce normal stitch loops and in an opposite direction to produce loops that are passed through and also around said stitch loops to lock same, and wherein at the termination of each course of locked stitches the thread is carried to and fro over a comparatively small number of additional needles which are operated to produce intermeshing stitches other than locked stitches constituting a selvedge for the locked stitch fabric.

7. A method of knitting selvedged fabric according to claim 1, of the type comprising courses of stitch loops alternating with courses of stitch-locking loops, in which the thread for a course of locking loops is supplied to a less number of needles than that to which it is supplied for a course of stitch loops and in which at the last formed end of a course of locking loops the thread from the last locking loop is fed to additional needles and the latter are operated to produce unlocked stitch loops intermeshing with similar stitch loops of a preceding course.
